DECORATIVE VEGETATION INHIBITING SUR- ROUND FOR GRAVE MARKING STRUCTURES

Joseph J. Matvey, 1100 Penn Center Blvd.—615,
Pittsburgh, Pa. 15235

Filed Feb. 11, 1972, Ser. No. 225,704

Term of patent 14 years

Int. Cl. D31

U.S. Cl. D79—2

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 1 is a top plan view of a decorative vegetation inhibiting surround for grave marking structures of this invention.

FIG. 2 is a bottom plan view of the decorative vegetation inhibiting surround for grave marking structures of this invention.

FIG. 3 is a cross sectional illustration of the surround taken through 3-3 of FIG. 1.

FIG. 4 is a cross sectional view, similar to FIG. 3, but showing another embodiment of the design with a modified profile.

FIG. 5 is a cross sectional view, similar to FIG. 3, but showing another embodiment of the design with a modified profile.

FIG. 6 is a fragmentary top plan detail showing another embodiment having V-shaped interior corner opening and a curved exterior corner in lieu of the rectangular exterior corners of FIG. 1.

FIG. 7 is a fragmentary top plan detail, similar to FIG. 6, but showing another embodiment having a generally rectangular interior corner opening communicating with the inner opening of the surround.

FIG. 8 is a fragmentary top plan detail, similar to FIG. 7, but showing another embodiment having a restricted throat interior corner opening.

FIG. 9 is a fragmentary top plan detail showing another embodiment having an inwardly open hollow upstanding boss in the interior corner.

FIG. 10 is a cross sectional view showing the hollow boss of FIG. 9 taken through 10-10 of FIG. 9.

FIG. 11 is a cross sectional view showing the hollow boss of FIG. 9 taken through 11-11 of FIG. 9.

For convenience of illustration, the distance between adjacent interior and exterior corners in FIGS. 6 through 9 has been shown as being substantially reduced with respect to that shown in FIGS. 1 and 2, but FIGS. 1 and 2 more accurately depict the preferred distance.

I claim:

The ornamental design for a decorative vegetation inhibiting surround for grave marking structures, substantially as shown and described.
